Assignors to James MacGregor Jr. of Willow N. Y.
Letters Patent No. 302. Dated July 22, 1850.

The Schedule referred to in these Letters Patent and making part of the same.

To all to whom these presents shall come:

Be it known, that we J. H. Conklin & A. W. Jones of the City of New York in the State of New York have invented or produced a new design for stoves and that the following is a full & clear & exact description of the same, reference being had to the accompanying drawing making part of this specification, in which fig. 3, is a view of the Wm. fig. 1, of the false top and of the top plate & fig. 2, of the bottom plate. Fig. 4, is one of the legs detached.

The same Letters indicate like parts in all the figures.

The design is intended to be cut in metal, in bold relief, & is composed of ornaments in arabesque.

(A) Fancy Head from which foliage starts each way & to which shell work is a ground.

(B) Bird of Paradise.

(C) Sparrow with foliage between them and the Bird of Paradise.

(D) is a flower.

(E) is a shield, certain portions of the foliage are omitted on the drawing but they are similar to those represented, the foliage being but slightly changed.

We claim as our invention and desire to secure by Letters Patent the above Design which is fully set forth in the drawings accompanying this description.

Witnesses.
